UNITED STATES PATENT OFFICE

FREDERICK A. HART, OF NEW BRITAIN, CONNECTICUT, ASSIGNOR TO REMINGTON TYPEWRITER COMPANY, OF ILION, NEW YORK, A CORPORATION OF NEW YORK

TYPEWRITING MACHINE

Application filed March 4, 1927. Serial No. 172,684.

My invention relates to typewriting machines, and more particularly to work sheet controlling and gaging means by which work sheets may be quickly, and successively, introduced and accurately positioned in the machine.

More specifically considered, my invention relates to paper guiding, and end-stop devices by which work sheets successively introduced rearwardly from the front of and beneath the platen may be quickly and accurately positioned.

The main objects of the invention, generally stated, are to provide improved and comparatively simple devices of the character specified, which are in the nature of attachments that may be readily incorporated in existing machines without modifying, or materially modifying, the existing structural features thereof, and which when desired may be readily attached to or detached from the machine as a single unit. A further object of my invention is to provide comparatively simple and compact devices of the character specified which are highly efficient in use and with the aid of which work sheets may be readily and accurately positioned under varying conditions of use.

To the above and other ends which will hereinafter appear, my invention consists in the features of construction, arrangements of parts and combinations of devices to be set forth in the following description and particularly pointed out in the appended claims.

In the accompanying drawings wherein like reference characters indicate corresponding parts in the different views

Fig. 1 is a detail perspective view of a portion of a carriage of a typewriting machine equipped with the devices of my invention.

Fig. 2 is a detail perspective view of one of the paper guides shown detached.

Fig. 3 is a detail perspective view of one of the flexible end-stop carrying arms shown detached.

Fig. 4 is a detail perspective view of one of the adjustable slides or carriers shown detached.

Fig. 5 is a detail transverse sectional view,

taken on the line 5—5 of Fig. 8 and looking in the direction of the arrows at said line.

Fig. 6 is an enlarged, detail perspective view of the eccentric, shown detached, by which the associated guide and stop carrying arm are held in adjusted positions.

Fig. 7 is a fore and aft vertical sectional view with parts broken away showing a portion of the carriage with the devices of my invention in place thereon.

Figs. 8 and 9 are somewhat similar views showing different adjustments of parts of the structure.

Fig. 10 is an enlarged, detail transverse sectional view taken on the line 10—10 of Fig. 8 and looking in the direction of the arrows at said line.

Fig. 11 is an enlarged, detail transverse sectional view taken through one of the flexible stop carrying arms, the section being taken on the line 11—11 of Fig. 3 and looking in the direction of the arrows at said line.

The present invention has some of the same general objects in view as the construction disclosed in the application of Cloyd E. Burns filed July 13, 1926, Sr. No. 122,239 and is in the nature of improvements on the construction disclosed in said application.

The devices of the present invention were devised more especially for use in the Remington front feed billing machines, certain features of which are disclosed in my application Sr. No. 120,403 filed July 3, 1926. While the devices of the present invention are particularly useful in the machine referred to, it should be understood that their use is not restricted to such machine, but that they may be employed in various forms of typewriting and like machines wherever found available.

In the accompanying drawings I have shown only so much of the said Remington machine as is necessary to arrive at an understanding of my invention in its embodiment therein.

Generally stated, the Remington machines above referred to are employed in various kinds of billing operations, where two or more work sheets are to be correlated in the machine and printed at a single operation.

However, I do not deem it necessary to describe specifically the many different forms of billing operations in which the said machines may be used. It is sufficient for an understanding of the present invention to describe in general terms one mode of billing that may be successfully carried out with the aid of said machines and perhaps briefly refer to some of the various other methods in connection with which the machines may be employed together with the paper end-stop and other devices of my invention.

One method of using the said machine which will be specifically referred to, is its employment, for example, for simultaneously, or at one writing, making out a bill or invoice and making corresponding entries on a record or register sheet which receives the entries written on all of the individual bill or invoice sheets. In the example referred to the register sheet and its accompanying carbon sheet remain in the machine. Means are provided for quickly entering a bill or invoice sheet and accompanying carbon sheet rearwardly into the machine from in front of the platen, and accurately positioning them in proper correlation with the previously introduced register sheet and the printing line. The entries may then be made on a bill sheet and these will be transferred through the interposed carbon sheet to the register sheet. The bill sheet and accompanying carbon sheet are then rapidly withdrawn from the machine without disturbing the register sheet, and another bill sheet with accompanying carbon sheet may then be quickly introduced and positioned as before, and so on.

In the example of the billing operations explained above the end stops and guides of my present invention are intended to coact with the bill or invoice sheet, to quickly and accurately effect a positioning thereof under varying conditions. It should be understood, however, that in other uses of the machine, the said stop devices of my invention will coact with other sheets in a variety of ways, some of which will be hereinafter explained.

With the foregoing general explanation, I will now proceed to briefly describe so much of the said machine as is necessary to arrive at an understanding of my invention in its embodiment therein.

The frame of the machine is of the usual construction and includes a top plate 1 carrying fixed guide rails 2 (only one of which is shown), oppositely grooved to receive cross anti-friction bearing rollers 3. These rollers are also received in oppositely grooved carriage rails 4 at the front and rear of the carriage (the rear carriage rail only being shown), said carriage rails being connected with the end bars 5 of the carriage.

The carriage, which is power driven in the

usual manner, is thus supported and mounted to travel from side to side of the machine over the top plate under control of the usual escapement mechanism (not shown), and in some instances under control of the usual tabulator mechanism.

The platen 7 is carried by the platen frame in the usual manner, said platen frame comprising end plates 8 united by suitable cross bars. The platen frame is connected to the carriage or truck by links 10 in the usual manner, which links ordinarily guide the platen frame in its case shifting movements. The present machine, however, is intended to write only with capital letters or upper case characters and there is, therefore, no case shifting movements of the platen and platen frame; the platen frame being firmly held in its upper case position on the carriage, where it will coact with the outermost types 11 on the type bars 12. These type bars are mounted in a type bar segment in the usual manner to swing upwardly and rearwardly to printing position where they strike against the front face of the platen.

The usual ribbon vibrator mechanism is employed so as to interpose the ribbon in the path of the types 11 at each actuation of a type bar. Only the upper end portion of the ribbon vibrator 13 is shown, it being understood, however, that the vibrator is guided for up and down movement on the type guide 14 in the usual manner.

As in the construction disclosed in my said prior application, there are two curved paper deflectors 15 and 16 employed beneath the platen, one arranged above the other and maintained spaced apart by intermediate spacing members or blocks 17 located near the ends thereof. Generally speaking, these deflectors beneath the platen conform substantially to the curvature of the latter, or are substantially concentric therewith, and extend substantially throughout the length of the platen. As thus constructed there are two separate channels provided, one of which is the open channel 19 between the two deflectors, and which is bounded at its ends by the spacing members 17, either or both of which may constitute side edge guides or gages for cooperation with one or both side edges of a sheet or sheets introduced into the channel 19. The other separated channel 20 is provided between the under surface of the platen and the upper deflector 15. It will be seen that the forward edge of the deflector 16 terminates in advance of the forward edge of the deflector 15. The deflector 16 is continued up at the rear to provide a paper table *a*, bent rearward at its upper edge portion, as at *b*, and terminating in an upper rear edge 21 at a considerable height above the platen. On the other hand, the deflector 15 terminates in the rear of the platen at a much lower point and below the

top of the platen, where it is bent to form a loop 22 that surrounds a rod 23 fixedly connected at its ends to the end plates 8 of the platen frame. In this manner the rigidly united deflectors 15 and 16, together with all of the parts carried thereby, are mounted on the rod 23. The construction is such that the deflector 15, is lightly pressed against the platen, or against the interposed sheets 10 R, R'. In this manner the sheets R, R', are held snugly against the platen and other sheets including the sheet B, intended to be introduced rearwardly into the channel 19 are prevented from entering the channel 20. In order to facilitate the backward introduction of sheets into the channel 19 from in front of the platen there is provided in accordance with the invention disclosed in my prior application, a guide, shield, or paper deflector 24 that is movable on the carriage from a substantially horizontally disposed ineffective position, shown in dotted lines in Fig. 7, to a downwardly and rearwardly inclined effective position, shown in full lines 25 in said figure, and vice versa.

The deflector 24 has depending arms 25 at the ends thereof, each of said arms being pivoted at 26 on an end plate 8 of the platen frame. In this manner the deflector 24 is 30 mounted for pivotal movement from the ineffective dotted line position, shown in Fig. 7, where it is out of the paths of the types, to the full line position where it crosses the printing line and extends in the 35 paths of the types. In this last mentioned position the deflector overlaps the forward edge of the deflector 16 and forms virtually a continuation of the channel 19 to aid in quickly and effectively introducing work sheets 40 backwardly beneath the platen into the channel 19.

It is unnecessary, for the purpose of the present invention, to disclose the means by which this deflector 24 is actuated and by 45 which the fine wire line indicator 27 is automatically shifted from the effective, to the ineffective position in Fig. 7, when the deflector 24 is shifted from the dotted to the full line position and vice versa. It also is 50 unnecessary to disclose herein the means by which these devices are automatically controlled by a shifting of the feed rollers 28 (diagrammatically shown) from the ineffective position shown in Fig. 7 into contact 55 with the platen or a work sheet thereon. Nor is it necessary to disclose the means for automatically lowering the ribbon vibrator from the full to the dotted line position in Fig. 7 when the deflector 24 is moved from ineffective 60 to effective position, thus giving ample clearance between said deflector and vibrator. All of such means are embodied in said hereinbefore mentioned Remington machines.

It will suffice for the purpose of arriving 65 at a better understanding of this invention, in

its present embodiment, to bear in mind that the parts referred to operate in the general manner indicated above.

As disclosed in said previously filed applications a set of feed rollers 30 coact only with the work sheet R and its carbon sheet R', whereas one or more additional sets of feed rollers 28 are employed, depending on the use of the machine as a so-called "two-sheet" biller, or for more than two work 75 sheets. In the present instance it is assumed that the machine is equipped as a two-sheet biller and a single set of aligned feed rollers 28 is diagrammatically represented in Fig. 7. The specific manner of mounting these feed 80 rollers for shifting movement into and out of cooperation with the work sheets with which they coact is disclosed in the hereinbefore referred to Remington machine and need not be specifically described herein. 85

In accordance with the present invention certain work sheet gaging means, or paper end-stops, coact with the bottom edge of a bill or invoice sheet B introduced through the channel 19, and these stops as well as certain 90 paper guiding devices, are adjustable supported and detachably mounted on the paper table a and may be readily applied or detached as a single unit. These devices of the present invention, and the manner of mounting and adjusting them, will now be described.

A casting, designated as a whole by the reference numeral 31, constitutes a support for a set of devices of my present invention, which devices are adjustable on said support, 100 and the support itself is provided with means by which it may be readily applied to and detached from the carriage with said devices and also may be adjusted to different positions with said devices longitudinally of the 105 platen. I preferably make this support of aluminum and in practice prefer to employ two of such supports, each equipped with said devices in a like manner and I locate the supports at different positions longitudinally 110 of the platen, as indicated in Fig. 1. I prefer to detachably and adjustably secure each support to the upper edge portion b of the paper table a and to this end I construct the supports 31 as follows:

Inasmuch as each support 31 and the parts carried thereby are alike, it will suffice to describe one of these units, it being understood that such description will apply to each of them. The support 31 is slotted at 32 120 throughout its length to provide a bearing slot closed at its rear side and of a width corresponding substantially to the thickness of the upper edge portion b of the paper table which is received therein and constitutes a 125 support for the members 31 and the parts carried thereby. In order to hold or clamp each support 31 in the position to which it may be adjusted along the paper table, and enable it to be removed when desired I pro- 130

vide a suitable clamping or clutching means that may be readily released. In the present instance such means are in the nature of a ball or roller clutch comprising two clutch balls 33 each received in a transverse opening or pocket 34 that communicates with and extends transversely of the slot 32. A longitudinally extending bore 35 in the support 31 receives two oppositely disposed wedges 36 each coacting with one of the balls 33. Each wedge has an inner integral cylindrical head 37 and an outer integral cylindrical finger piece or head 38 both of which fit loosely in the bore 35. A coiled expansion spring 39 bears at its opposite ends against the heads 37 and tends to move the wedges outward away from each other. This results in each wedge acting on its associate ball 33, tending to force it into clutching engagement with the part *b* of the paper table, when said part is contained in the slot 32, and firmly hold the support on the paper table. In order to release the clutch it is merely necessary to press the associated finger pieces 38 towards each other, thus releasing the pressure of the wedges on the balls and freeing the clutch. It will be understood that each ball 33 is received between the two companion heads 37 and 38 and that therefore the wedges cannot be displaced from their bore 35 as long as the balls remain in their pockets 34. In order to readily assemble the clutch members, and enable them to be taken apart when desired, I provide a tapped opening in register with each pocket 34 and provide a filling screw 40 which is received in and normally closes its opening, the inner end of each screw being substantially flush with the lower wall of the slot 32. When assembling the clutch members the screws 40 are removed and the balls 33 are introduced through the tapped openings into the pockets 34 while the wedges are held against the pressure of their spring 39. The screws 40 are then threaded into place and the clutch is ready for use.

The support 31 is provided with an inclined supporting face 41 (see Fig. 7) bordered on each side with an upstanding flange 42. This supporting face and side flanges act as a support and guide for an auxiliary supporting member, designated as a whole by the reference numeral 44, and which is shown detached in Fig. 4. This member has parallel side flanges 45 that terminate at their lower ends in upstanding ears 46 having registering openings 47 therein. A spindle 48 (see Fig. 6) receives a bearing in said openings and is provided at one end with a laterally bent arm 49 that constitutes a finger piece by which the spindle may be turned in its bearings. Fixed on said spindle by a pin 50, or otherwise, is an eccentric 51 that constitutes a clamping member, as will presently appear. This eccentric extends between the

ears 46 and the high portion of the eccentric moves towards and away from the outer face of the auxiliary support, depending on the direction in which the finger piece 49 is turned. The bottom wall of the auxiliary support 44 is slotted longitudinally thereof, as at 52, and each side wall of the slot is cut away to provide a web 53, as shown in Figs. 5 and 10. The stem of a screw 54 passes through a circular opening in the support 31 and through the slot 52 in the member 44. This screw is provided at its forward end with a head 55, flattened at its sides, as indicated at 56 in Fig. 5, to engage opposite parallel side walls 57 of the cut-out in the face of the member 44 and adapted also to bear down on the web 53 thereof. This prevents the screw 54 from turning while a thumb nut 58 on the rear threaded end thereof is turned. An extension or hub 59 on the thumb nut bears at its forward end against the rear side of the support 31 and when the nut is tightened the head of the screw will firmly clamp the auxiliary support 44 in its adjusted position on the support 31. When said screw is loosened the auxiliary support 44 may receive a sliding adjustment in an inclined plane towards and from the platen, from, for example, the position shown in Fig. 7, to that indicated in Fig. 9, or vice versa, or to any intermediate point. This adjustment of the member 44 is parallel with the face of the paper table *a*, the member being supported and guided by the face 41 and the side flanges 42 of the support 31. When the desired point of adjustment is obtained, the thumb-nut 58 is tightened, firmly clamping the member 44 in such position.

A coiled expansion spring 60 surrounds the part 59 of the thumb nut 58, bearing at one end against the rear side of the support 31 and at its opposite end against the head of the thumb nut. The purpose of providing this spring is to insure at all times the maintenance of the head of the screw 54 in its longitudinally extending groove or cut-out in the face of the auxiliary support 44, with the flat sides of said head engaging the walls 57 as described, even though the thumb nut be loosened to the limit of its movement on the screw. In order to limit the releasing movement of the thumb nut I prefer to provide a slight head or burr 61 on the rear end of the screw 54.

Supported on the forward face of the auxiliary supporting member 44 is a thin flexible metal arm 62 which is shown detached in Fig. 3. The width of this arm is such that it may be received between and guided by the side flanges 45 of the auxiliary support 44. This arm constitutes a carrier for a paper end-stop 63 formed by an enlargement on the lower end of the arm and against which the bottom edge of a work sheet may be arrested, as will hereinafter appear. The arm 62 may

be adjusted towards and from the platen on the auxiliary support 44, and the flexibility of the arm enables it to assume a bent condition around the platen when the arm is adjusted to a lower position, as indicated, for example, in Fig. 9. The arm 62 preferably has fixed thereto a forwardly projecting pin 64 which may be riveted to the arm, as indicated at 65 in Fig. 11, and firmly held thereto by 10 a reinforcing washer 66. This pin provides means that facilitate an adjustment of the arm on its support towards and from the platen, and at times acts as a stop to limit the range of such adjustment and to prevent the arm from being accidentally detached from its supporting means.

Arranged above the flexible arm and loosely fitting between the side flanges 45 of the auxiliary support is a stiff sheet metal paper 20 guide 67, shown detached in Fig. 2. This guide has forwardly bent ends 68 and 68^a between which is located a centrally disposed longitudinally extending slot 69 in which may be received, at times the pin 64 on the flexible 25 arm, as for example, when the parts assume some such adjusted relation as that indicated in Fig. 9.

It will be understood that the paper guide 30 67 is at all times located directly beneath the eccentric 51 so that when the latter is turned to clamping position it will bear down against the paper guide. The latter will in turn bear down against the underlying flexible arm 62 pressing it against the forward face of the auxiliary support 44. Means are thus provided for firmly clamping and holding the paper guide and end-stop carrying-arm in the positions to which they may be relatively adjusted on the auxiliary support, which in itself is adjustable on the support 31, as hereinbefore pointed out.

In thus supporting the paper guide 67 on the support 31, it will be seen that said guide is arranged parallel with the paper table *a* 45 providing an intervening space 70 between the under side of said guide and the front face of the paper table *a*. It will be seen moreover that such space 70 forms in effect a continuation of the passage or channel 19 between the curved deflectors 15 and 16 and receives and guides sheets passing therefrom.

When in condition for use the paper guide 67 will be adjusted on its support down to the position represented in the drawings with the lower bent end 68^a thereof resting on top of the looped portion 22 of the deflector 15, thus forming a continuation of the channel 19, as hereinbefore indicated. This position of the guide 67 is maintained irrespective of the position to which the companion end-stop 63 and its arm 62 may be adjusted, as will be understood from a consideration of Figs. 7, 8 and 9. Fig. 7 represents the highest point of adjustment of the stop 63, Fig. 9, one of 65 the lower points of adjustment thereof, and

Fig. 8 an intermediate point of adjustment of said stop. It will be seen that at times the stop 63 is located in the space 70 between the paper guide 67 and the paper table *a*, whereas at other times it is located in the channel 19 70 between the two paper deflectors 15 and 16.

When it is necessary to effect a relative adjustment between the members 62 and 67 which will bring the pin 64 outside of the slot 69, and beyond the upper end 68 of the 75 guide 67, as shown in Figs. 7 and 8, such adjustment may be effected as follows:

The eccentric 51 is released and the guide 67 is adjusted up on the support 44 until the lower end 68^a of the guide is adjacent the 80 eccentric 51. At this time the upper end of the guide may be tilted forward around the eccentric to free the slotted portion of the guide from the pin 64. The flexible arm 62 may then be adjusted up with the aid of its 85 pin until the latter is beyond the upper end 68 of the guide. The guide 67 is then turned back against the flexible arm and adjusted to effective position and the flexible arm may then be adjusted towards, or away from the 90 platen, or around the same to properly locate the end-stop 63. The eccentric is then turned to clamping position and the guide and flexible arm will be firmly held in their positions 95 of relative adjustment.

It will be understood that the pin 64 coacts with the eccentric 51 to limit the downward adjustment of the arm 62. Therefore, it is necessary in order to afford an adjustment of the arm 62 to its lower positions (one of 100 which is indicated in Fig. 9) to carry the eccentric 51 down from a position where it obstructs the requisite downward adjustment of the pin 64 and the arm to which it is connected. This result is attained by adjusting the 105 auxiliary support 44 down on the support 31, as indicated for example in Fig. 9, which affords an adjustment of the end-stop 63 to its furthest advanced position.

While I have referred specifically to one 110 end-stop 63, guide 67 and associated parts, as hereinbefore indicated, I prefer to employ two sets of such devices as shown in Fig. 1, the devices of each set being adjustable together as a single unit with their support 31 115 longitudinally of the platen to accord with bill sheets, etc., of different widths; each support 31 also being readily attachable to and detachable from the paper table with the aid of the ball clutch.

After the register sheet R and its carbon sheet R' have been positioned as described, a bill or invoice sheet B is introduced rearwardly into the channel 19 and positioned with the aid of the line indicator 27 for the first writing line position. The feed rollers 28 are then contactively engaged with the bill sheet to hold it in its adjusted position. The paper end-stops 63 are then adjusted down to contact with the bottom edges of the bill 130

- sheet thus introduced and are secured in their adjusted positions. The writing may then proceed and each subsequently entered bill sheet may be quickly entered and positioned 5 with the aid of the end-stops 63 to begin the first written line thereon, while the register sheet and its carbon remain in the machine, the register sheet taking an accumulation of the written bills.
- 10 It will be understood that the part 31 may be regarded as a support adjustable longitudinally of the platen and the devices 44 and 62 as a two-part stop-carrying member mounted on said support, the two parts (44 15 and 62) of said member being mounted for relative bodily adjustment one on the other in a line feed direction, one of said parts (62) being flexible and carrying a paper end-stop 63.
- 20 I have hereinbefore indicated that the present machine is capable of a very wide range of use, and may be employed with or without slight change in almost any character of billing or like work wherein two or 25 more sheets are employed, and where one or more work sheets are introduced into and removed from the machine, while another or other sheets are retained in the machine and a certain correlation is required between 30 the sheet or sheets retained in the machine and those introduced therein from time to time. Therefore, the end stops may be employed in a variety of ways.

For example, let it be supposed that the 35 machine is to be used as a check writing machine, in which a copy is to be made of all checks as they are written. In this event the checks only would be rearwardly introduced into the channel 19, the end-stops 63 being advanced to some such position as 40 that indicated in Fig. 9 and permitted to remain in such position indefinitely. The record of the checks written would be manifolded through the carbon sheet R' to the 45 record sheet R, both of which latter sheets are fed through the separate channel 20. In this event the sheet R would constitute a "pay-roll" or "register" sheet, the use of the stops 63 in check-writing providing for the 50 adjustment of such stops to accord with checks of different depths.

Generally speaking, the sheet R, if used when copying bills or invoices, may constitute a "sales" sheet or a "distributing" sheet. 55 If used in check-writing it may constitute a "pay-roll" or "register" sheet. In each event, however, the sheets R and R' remain in the machine while the bill sheet and accompanying carbon or the check, as the case may be, 60 are removed after each writing, and new sheets entered in place thereof with the aid of the end-stops and paper guides of my invention.

In a companion application filed of even 65 late herewith Sr. No. 172,685 I have included

features which are covered by claims of the present application; the claims in said companion application being restricted to features not disclosed herein.

In said companion application the end-stop devices and guides are capable of co-acting with relatively long work sheets, such as ledger sheets for example, but where relatively shorter sheets within the range of adjustment of the end-stops 63 of the present 70 construction are employed, I prefer to use the devices of the present construction, since they are more readily applied to the existing machine and are lighter and more compact.

What I claim as new and desire to secure 80 by Letters Patent, is:—

1. In a typewriting machine, the combination of a cylindrical platen, a support, a two-part stop-carrying member mounted on 85 said support, the two parts of said member being mounted for relative bodily adjustment one on the other in a line feed direction, one of said parts being flexible and carrying a paper end-stop, the flexibility of 90 the flexible part enabling it to bend to a curved condition which conforms generally to the curvature of the platen, and means for holding said flexible part in place around the platen in such curved condition.

2. In a typewriting machine, the combination of a cylindrical platen, a support, means for affording an adjustment of said support to different set positions longitudinally of the platen, a two-part stop-carrying member mounted on said support, the two parts of said member being mounted for relative bodily adjustment one on the other in a line feed direction, one of said parts being flexible and carrying a paper end-stop, 100 the flexibility of the flexible part enabling it to bend to a curved condition which conforms generally to the curvature of the platen, and means for holding said flexible part in place around the platen in such curved condition.

3. In a typewriting machine, the combination of a cylindrical platen, a support, a two-part stop-carrying member mounted for adjustment in a line space direction on 115 said support, the two parts of said member being mounted for relative bodily adjustment one on the other in a line feed direction, one of said parts being flexible and carrying a paper end-stop, the flexibility of 120 the flexible part enabling it to bend to a curved condition which conforms generally to the curvature of the platen, means for holding said flexible part in place around the platen in such curved condition, and means for holding the two parts of the stop-carrying member against accidental relative displacement from the position of relative 125 bodily adjustment in which they are set.

4. In a typewriting machine, the combination of a carriage, a cylindrical platen 130

carried thereby, a support on the carriage, a second support adjustable longitudinally of the platen on said first mentioned support, a flexible paper end-stop carrying-arm adjustable in a line feed direction on said second support, the flexibility of said arm enabling it to bend to a curved condition which conforms generally to the curvature of the platen and means for holding said arm in a

10 curved condition around the platen.

5. In a typewriting machine, the combination of a cylindrical platen, a paper table, a support detachably connected with and adjustable along the paper table longitudinally 15 of the platen, a flexible paper end-stop carrying-arm adjustable on said support, the flexibility of said arm enabling it to bend to a curved condition which conforms generally to the curvature of the platen, and means 20 for holding said arm in a curved condition around the platen.

6. In a typewriting machine, the combination of a cylindrical platen, a paper table, a support adjustable along the paper table 25 longitudinally of the platen, a flexible paper end-stop carrying-arm mounted for sliding adjustment on said support towards and away from the platen, the flexibility of said arm enabling it to bend to a curved condition which conforms generally to the curvature of the platen, means for holding said arm in a curved condition around the platen, and releasable means for holding said arm 30 in its position of adjustment on said support.

35 7. In a typewriting machine, the combination of a cylindrical platen, a support adjustable longitudinally of the platen, a paper guide adjustable on said support towards and away from the platen, a flexible paper end-stop carrying-arm adjustable on said support towards and away from the platen, the flexibility of said arm enabling it to bend to a curved condition which conforms generally 40 to the curvature of the platen, and means for holding said arm in a curved condition around the platen.

45 8. In a typewriting machine, the combination of a paper table, a cylindrical platen, means for directing paper inserted from the front of and beneath the platen rearwardly and upwardly, and a paper guide in the rear of the platen and overlying said paper table and fixed against movement out of parallelism therewith to receive and guide the rearwardly inserted paper between said guide and the paper table, and means for adjusting said guide lengthwise towards and from the platen.

50 9. In a typewriting machine, the combination of a paper table, a cylindrical platen, means for directing paper inserted from the front of and beneath the platen rearwardly and upwardly, a paper guide in the rear of the platen and overlying said paper table and 55 constantly maintained fixed against move-

ment out of parallelism therewith, said paper guide coacting directly with said directing means to receive and guide the rearwardly inserted paper between said guide and the paper table, means for adjusting said guide lengthwise towards and from the platen, and separate means for adjusting said guide longitudinally of the platen.

10. In a typewriting machine, the combination of a cylindrical platen, means for directing paper inserted from the front of and beneath the platen rearwardly and upwardly, a paper table in the rear of the platen that receives the paper introduced as specified, a rigid paper guide that overlies the paper table in constantly maintained parallel arrangement therewith and out of contact with the platen, said paper guide coacting directly with said directing means to receive the rearwardly inserted paper and guide it between said guide and the paper table, and means for adjusting said paper guide endwise towards and from the platen and also longitudinally of the platen.

11. In a typewriting machine, the combination of a cylindrical platen, means for directing paper inserted from the front of and beneath the platen rearwardly and upwardly, an overlying paper guide to receive and guide the paper thus introduced, means for adjusting said guide, a paper end-stop carrying-arm underlying said guide, and means for adjusting said arm.

12. In a typewriting machine, the combination of a cylindrical platen, means for directing paper inserted from the front of and beneath the platen rearwardly and upwardly, an overlying paper guide to receive and guide the paper thus introduced, a paper end-stop carrying-arm underlying said guide, and means that enable said guide to be adjusted towards and from the platen and enable the end-stop carrying-arm to be adjusted relatively to said guide towards and from the platen.

13. In a typewriting machine, the combination of a cylindrical platen, means for directing the paper inserted from the front of and beneath the platen rearwardly and upwardly, an overlying paper guide to receive and guide the paper thus introduced, a paper end-stop carrying-arm underlying said guide, means that enable said guide to be adjusted towards and from the platen and enable said end-stop carrying-arm to be adjusted in said direction relatively to said guide, and means which enable said guide and arm to be adjusted together longitudinally of the platen.

14. In a typewriting machine, the combination of a cylindrical platen, means for directing paper inserted from the front of and beneath the platen rearwardly and upwardly, an overlying paper guide to receive and guide the paper thus introduced, means for detaching and adjusting said guide, a flex-

ible paper end-stop carrying-arm, the flexibility of said arm enabling it to bend to a curved condition around the platen, and means which enable said arm to be adjusted relatively to said guide to bring the stop carried by said arm either in advance of or back beyond the forward end of said guide.

15. In a typewriting machine, the combination of a cylindrical platen, means for directing paper inserted from the front of and beneath the platen rearwardly and upwardly, an overlying paper guide to receive and guide the paper thus introduced, means for adjusting said guide, a flexible paper end-stop carrying-arm, the flexibility of said arm enabling it to bend to a curved condition around the platen, means which enable said arm to be adjusted relatively to said guide, and a single means by which said guide and arm are held against accidental displacement from their positions of adjustment.

16. In a typewriting machine, the combination of a cylindrical platen, means for directing paper inserted from the front of and beneath the platen rearwardly and upwardly, an overlying paper guide to receive and guide the paper thus introduced, means for adjusting said guide towards and from the platen, a flexible paper end-stop carrying-arm underlying said guide, the flexibility of said arm enabling it to bend to a curved condition around the platen, means which enable said arm to be adjusted relatively to said guide, and means for enabling said guide and arm to be adjusted to different positions longitudinally of the platen.

17. In a typewriting machine, the combination of a cylindrical platen, means for directing paper inserted from the front of and beneath the platen rearwardly and upwardly, a paper table in the rear of the platen that receives the paper introduced as specified, a paper guide that overlies the paper table in parallel arrangement therewith, means for adjusting said paper guide, a flexible arm underlying said guide and carrying a paper end-stop received between said guide and the paper table, and means that enable the flexible arm to be adjusted and advanced relatively to said guide to a position where the arm will assume a bent condition around the platen.

18. In a typewriting machine, the combination of a cylindrical platen, means for directing paper inserted from the front of and beneath the platen rearwardly and upwardly, a paper table in the rear of the platen that receives the paper introduced as specified, a support adjustable on said paper table longitudinally of the platen, a paper guide carried by and adjustable with said support and arranged parallel with the paper table, an arm carried by and adjustable with said support and arranged beneath said guide, and a paper end-stop carried by said arm.

19. In a typewriting machine, the combination of a cylindrical platen, means for directing paper inserted from the front of and beneath the platen rearwardly and upwardly, a paper table in the rear of the platen that receives the paper introduced as specified, a support adjustable on said paper table longitudinally of the platen, a paper guide carried by and adjustable with said support and arranged parallel with the paper table, an arm carried by and adjustable with said support and arranged beneath said guide, a paper end-stop carried by said arm, and means that enable said paper guide and said stop-carrying arm to be adjusted on said support towards and away from the platen.

20. In a typewriting machine, the combination of a cylindrical platen, means for directing paper inserted from the front of and beneath the platen rearwardly and upwardly, a paper table in the rear of the platen that receives the paper introduced as specified, a support adjustable on said paper table longitudinally of the platen, a paper guide carried by and adjustable with said support and arranged parallel with the paper table, a flexible arm carried by and adjustable with said support and arranged beneath said guide, a paper end-stop carried by said arm, and means which enable said flexible arm to be advanced beyond the range of said guide and because of the flexibility of said arm to assume a curved condition around the platen.

21. In a typewriting machine, the combination of a platen, a paper table, a support, a hand releasable ball clutch by which said support is detachably secured to and may be adjusted on said paper table in the direction of the length of the platen, a paper guide and a paper end-stop mounted on said support and each adjustable thereon towards and from the platen, and means for securing said paper guide and end-stop against accidental displacement from their adjusted positions.

22. In a typewriting machine, the combination of a platen, a paper table, a support, a hand releasable ball clutch by which said support is detachably secured to and may be adjusted on said paper table in the direction of the length of the platen, a paper guide mounted on said support, a flexible arm mounted on said support for adjustment towards and from the platen, the flexibility of said arm enabling it to assume a curved condition around the platen, a paper end-stop carried by said arm, and means coacting with said arm for holding it around the platen in such curved condition.

23. In a typewriting machine, the combination of a platen, a paper table, a support, means that enable said support to be detached from the paper table and to be adjusted along the same to different positions thereon longitudinally of the platen, a paper guide carried by said support and arranged parallel with

the paper table, and a paper end-stop adapted to coact with an edge of a work sheet controlled by said guide, and means for adjusting said end-stop towards and from the platen.

24. In a typewriting machine, the combination of a platen, a paper table, a support, means that enable said support to be detached from the paper table and to be adjusted along 10 the same to different positions thereon longitudinally of the platen, a paper guide carried by and adjustable with said support and arranged parallel with the paper table, a flexible arm carried by and adjustable with said 15 support, a paper end-stop carried by said flexible arm beneath said paper guide, the flexibility of said arm enabling it to assume a curved condition around the platen, and means for affording an adjustment of the 20 paper guide on said support towards and away from the platen and for affording an adjustment of the flexible arm in a like direction relatively to said paper guide.

25. In a typewriting machine, the combination of a platen, a paper table, a support, a hand releasable ball clutch carried by said support and by which the support is detachably secured to and may be adjusted on said paper table, and a paper controlling device 30 carried by said support, whereby said support, releasable ball clutch and the paper controlling device may as a single unit be readily adjusted on and detached at will from said paper table.

- 35 26. In a typewriting machine, the combination of a platen, a paper table, a support, a hand releasable ball clutch carried by said support and by which the support is detachably secured to and may be adjusted on said 40 paper table, and a paper controlling device carried by and adjustably mounted on said support, whereby the paper controlling device may be adjusted on its support without disturbing the support and whereby said support, releasable ball clutch and the paper controlling device may as a single unit be readily adjusted on and detached at will from said paper table.

- 50 27. In a typewriting machine, the combination of a platen paper table, a support, a hand releasable ball clutch carried by said support and by which the support is detachably secured to and may be adjusted on said paper table, and a plurality of paper controlling devices carried by said support, whereby said support, releasable ball clutch and the plurality of paper controlling devices may as a single unit be readily adjusted on and detached at will from said paper table.

- 60 28. Signed at the borough of Manhattan, city of New York, in the county of New York and State of New York this 2nd day of March, A. D. 1927.
